UNITED STATES PATENT OFFICE

115,992

DESIGN FOR A TEXTILE FABRIC

Curt E. Forstmann, Montclair, N. J.

Application January 21, 1938, Serial No. 74,465

Term of patent 3½ years

To all whom it may concern:

Be it known that I, Curt Erwin Forstmann, a citizen of the United States, residing at Montclair, in the county of Essex and State of New Jersey, have invented a new, original, and ornamental Design for Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design consists in the warp and filling yarns having different twists and being so arranged that the resulting effect of the fabric gives a suggested herringbone shadow appearance derived from the warp yarns and a suggested cross bar appearance derived from the filling yarns.

I claim:

The ornamental design for a textile fabric as described and as shown.

CURT E. FORSTMANN.
